UNITED STATES PATENT OFFICE.

BENJAMIN EDWARD MEACHAM, OF LORAIN, OHIO, ASSIGNOR TO AMERICAN STOVE COMPANY, OF ST. LOUIS, MISSOURI, A CORPORATION OF NEW JERSEY.

THERMOSTATIC OVEN-HEAT REGULATOR.

Application filed November 16, 1926. Serial No. 148,651.

This invention relates to improvements in thermostatic oven heat regulators, and is an improvement on the general type disclosed in my Patent No. 1,236,335, dated October 5 7, 1917.

As shown in the said patent the vertical housing has a considerable cross sectional area and it occupies considerable space beyond the oven in which it controls the 10 amount of heat.

Gas stoves are frequently used in close quarters, and in small apartments space means a great deal.

One object of the present invention is to 15 so construct the parts that the said housing can be made of a cross section considerably less than is required in the said patent, and at the same time make a device that is simple in construction, durable, long lived in 20 operation, as well as occupying considerably less space.

In carrying out the above ideas I have utilized a structure that has many novel features that will be pointed out hereinafter.

25 In the accompanying drawings:

Figure 1 is a vertical longitudinal sectional view of a thermostatic heat regulator embodying my improvements, said gas valve being shown in open position.

30 Figure 2 is a sectional view similar to Figure 1, with the exception of the parts and the gas valve actuated thereby are shown in their closed positions.

Referring now to the drawings in which 35 similar reference characters denote the same parts, 1 is a vertical tube, which in the present instant is composed of a round gas pipe member that has its ends 2 externally screw threaded, and receiving the inner ends 40 of an upper casting head 3 and a lower casting head 4 screwed in position on the respective ends of the housing 1. This member 1 is preferably composed of a gas pipe that in full size is about one inch in external 45 diameter.

Extending vertically within the housing 1 is a vertical lever 5 that consists of a round member having its lower end 6 reduced and passing through a vertical opening 7 formed 50 in a slightly enlarged portion of the valve stem 8. This housing 4 has at the oven side of the housing a nipple 9 or other similar device attached, the said nipple adapted 55 to feed gas to the oven burner (not shown).

The upper end 10 of the lever 5 is pref-

erably made of a separate piece screw threaded to the said member as at 11. This member 10 extends upward into the top housing 3, its upper end 12 spanning a shaft 13 and coacting with the said shaft in a 60 manner to be presently explained.

A copper tube 14 has one end fastened or anchored to the head 3, and extending within this anchored end of the tube is a second tubular member 16, the outer end of the 65 member being open. Passing through the copper tube 14 is a porcelain or other substantially non-expansive member 17. One end of this porcelain member engages a cap 16' closing one end of said tube and the 70 other end of the porcelain member 17 engages the closed end 18 of the member 16. It is well understood by those skilled in this art that the copper tube expands and contracts as it is heated and cooled. As 75 the copper tube 14 expands, the porcelain member moves outward in respect to the head 3, and as the tubular member contracts, the porcelain member moves inward, moving with it the tubular member 16. The 80 expanding and contracting, therefore, of the copper tube causes the end 18 to push inward against a bulged portion 19, allowing the said member to follow its movement, and when the copper tube contracts, then the 85 porcelain member pushes the end 18 against the bulged portion, moving the member 10.

A spring actuated member or cup 20 is located in the wall of the head 3 opposite to the said copper tube 14 and also the porcelain member 17 and between the porcelain member and the upper head portion 12. This member 20 is normally pushed inward by a suitable coil spring 21, and engages a slightly outwardly bulged portion 22, the said 95 bulged portion carrying an outwardly extending pin 23 that passes through the inner end of the member or cup portion 20.

The shaft 13 has its inner end 24 screw threaded into the head 3, the outer end of 100 the said screw threaded portion being closed by a suitable screw 25. The opposite or outer end of the shaft 13 carries a suitable wheel 26 by means of which the shaft 13 is rotated in the said head 3 and the shaft 105 caused to move endwise by being rotated in a manner which will be presently explained.

Referring now to the valve stem 8, it is provided at its inner end with a tapered valve 27, its opposite end 28 projecting into an 110

opening 29 formed in a plug 30 that serves to guide and limit it for a purpose that will be referred to presently. The opposite valve end 27 coacts with an opening 31 for regulating and controlling the amount of gas passing through the nipple 9.

In operation gas is preferably fed to the housing 1 through an opening 32 that is formed in its upper end, a pipe (not shown) being screw threaded into the said opening. For the purpose of explaining the operation of this construction, in Figure 1, I have shown the wheel 26 adjusted to the 550° temperature mark, and the remaining parts being in their corresponding positions. It will be observed that when the wheel is so adjusted, the part 33 is out of engagement with the inner surface 34 of the upper extremity or head 12 of the lever 5. When in this position gas freely passes through the nipple 21 for heating the oven (not shown). As the oven is being heated, the copper tube 14 expands, or lengthens and the porcelain member 17 moves inward with the said expansion tube 14. It moves inward until the surface 34 and its head 12 is in contact with the part 33 of the shaft 13, at which time the expansion tube 14 continues and the said spring actuated member 20 forces the parts into the position shown in Figure 2, namely with the valve 27 closing the nipple opening 31 and cutting the gas off. When the oven cools a little, then the contraction of the copper tube 14 forces the porcelain member 17 inward, moving the said lever 5 so as to open the nipple opening 31, thus permitting gas again to flow to the burner within the said oven, thereby maintaining the heat in the oven to the degree to which the device is set, viz., 550°.

The gas supply tube (not shown) which is fastened to the opening 32 of the head 3, has the ordinary shut-off valve or cock (not shown). When this valve is closed, the gas is cut off from the housing 1 and the oven and the copper tube 14 begins to cool. As the oven and the copper tube 14 cool, the tube contracts, forcing the porcelain member 17 inward by engagement with the bulged portion 19 and this goes on until the parts reach the positions shown in Figure 1, with the outer end of the valve stem 8 against the wall of the opening 29. In order to reach the positions shown in Figure 1, the spring actuated member 20 is pushed inward, thus carrying the head 12 out of engagement with the part 33 of the shaft 13. From the foregoing it will be observed that the valve 27 is always wide open until a contact is made between the surface 34 and the part 33 of the shaft 13 and no movements of the valve will take place until this contact is made. In this operation the spring actuated member 20 is the closing off means, and the contraction of the copper tube is the

opening means for the said valve, thus closing off and permitting the flow of gas through the nipple.

From the foregoing description the operation of the mechanism for controlling the flow of gas through the nipple and thereby controlling the flame of the burner in the oven also controls the heat of the oven. By setting the wheel 26 to any desired degree on its edge denoting a certain degree of heat, then the heat in the oven will be controlled to that degree.

It will be noted from the foregoing description that in a sense the part 33 may aptly be referred to as a floating fulcrum. By this is meant that it does not act as a fulcrum until the surface 34 of the head 12 is brought into contact with it due to the expansion of the copper tube 14.

In Figure 1 the regulating wheel 26 is set at 550 to which the pointer 26' is pointed. This regulating wheel is provided with a stop 28' that is adapted to engage the pointer 26' which will prevent the wheel from being continuously rotated and thereby thrown out of adjustment. The wheel 26 in Figure 2 is set at the same temperature as it is in Figure 1 but in Figure 2 the heat of the oven is raised to the temperature of 550°, thereby closing the valve 27.

It should be understood that variations and changes may be made in the construction herein described and shown, so long as the changes do not take the construction outside of a fair interpretation of the appended claims.

Having thus described my invention, what I desire to claim and secure by Letters Patent of the United States is:

1. A thermostatic oven heat regulator comprising a movable lever, a fuel valve operatively connected with one end of the lever, a thermostatic element engaging the said lever near its opposite end, a fulcrum located beyond the said thermostatic member, the end of said lever adapted to engage the said fulcrum, and means located between the fulcrum and the said thermostatic member, said means constantly pressing the lever against the thermostatic member and adapted to press the end of the lever against said fulcrum.

2. A thermostatic oven heat regulator comprising a housing having at one end a fuel outlet, a lever within the said housing, a fuel valve adapted to close the said outlet, said fuel valve connected with one end of the said lever, a thermostatic member located adjacent the opposite end of said lever and engaging it, an adjustable fulcrum adapted to engage the lever beyond the thermostatic member and a pressure device located between said fulcrum and said thermostatic member, causing the said lever to follow the movement of the thermostat, and causing the

end of the lever to engage the said adjustable fulcrum for the purpose specified.

3. A thermostatic oven heat regulator comprising a housing, a lever located in the said housing, the housing having a fuel outlet, a fuel valve located in the housing and adapted to open and close said outlet, one end of the lever operatively connected with the fuel valve, an adjustable fulcrum located beyond the said thermostat and adapted to engage the same side of the lever as the thermostat, and a spring actuated member located at the opposite side of the lever and engaging it at a point between the thermostat and the fulcrum, the parts operating as specified.

4. A thermostatic oven heat regulator comprising a housing, a fuel outlet located in the said housing, a movable element having one member connected with the said fuel valve, a thermostatic member engaging said element near its opposite end, an adjustable fulcrum adapted to engage the same end of the element, and pressure means engaging the element between the thermostatic member and the fulcrum and pressing said element towards both the last mentioned elements, said housing provided with means for limiting the opening movement of the fuel valve.

5. A thermostatic oven heat regulator comprising a housing having a fuel outlet, a fuel valve cooperating with the outlet, a vertical lever having one end connected with the fuel valve, a thermostatic member engaging the opposite end of said lever and on the same side as the fuel valve, the fuel

valve having a stem portion adapted to engage the said housing for limiting its opening movement.

6. A thermostatic oven heat regulator comprising a housing having a fuel outlet, a fuel valve cooperating with the outlet, a lever having one end connected with the fuel valve, a thermostatic member engaging the opposite end of the lever and on the same side thereof as the fuel valve, an adjustable fulcrum adapted to engage the end of the lever adjacent the thermostatic member and on the same side as the thermostatic member, a pressure device located on the opposite side of the lever and pressing it against the thermostatic member and towards said fulcrum, and means limiting the opening movement of the said valve, the parts operating as described.

7. A thermostatic oven heat regulator comprising a movable element having one end operatively connected with a fuel valve, the opposite end of said element having two separated fulcrums located on one side of the element and an intermediate fulcrum located on the opposite side thereof, a thermostatically actuated member engaging the lower of said fulcrums, a spring actuated member engaging the intermediate fulcrum on the opposite side of said element, and an adjustable member adapted to be engaged by the remaining element, whereby the parts are adapted to operate in the manner described.

In testimony whereof I hereunto affix my signature.

BENJAMIN EDWARD MEACHAM.
